(57) **CLAIM**

The ornamental design for a smart watch, as shown and described.

DESCRIPTION

This application is related to application 29/669,190 filed Nov. 6, 2018, which is incorporated entirely by reference herein for all purposes.

FIG. 1 is a top, right side isometric view of our new design for a smart watch with the bands attached;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a back view thereof;

FIG. 8 is a to right side isometric view of the smart watch of FIG. 1 with the bands in the clasped position; and,

FIG. 9 is an exploded isometric view of FIG. 1.

The features shown in broken lines in the drawing depict portions of the smart watch that form no part of the claimed design.
